UNITED STATES PATENT OFFICE.

EDWARD M. WARING, OF BROOKLYN, NEW YORK.

CLOTH-CUTTING MACHINE.

1,209,524.

Specification of Letters Patent. Patented Dec. 19, 1916.

Application filed July 22, 1914. Serial No. 852,415.

To all whom it may concern:

Be it known that I, EDWARD M. WARING, a citizen of the United States of America, and a resident of Brooklyn, Kings county, 5 New York, have invented certain new and useful Improvements in Cloth-Cutting Machines, of which the following is a specification.

This invention relates to cloth cutting machines and the object of the invention is 10 to improve the construction of the machine in general and to add certain novel and useful features with a view of increasing the efficiency of the machine and improving the 15 operation thereof.

More particularly the improved and novel features of the invention relate to the means for supporting the motor and the arrangement and operation of the sharpening means 20 and the knife guard. In this respect this invention is a continuation of and improvement upon the invention described in my pending application Serial Number 787,070.

The several objects of the invention and the 25 manner in which I propose to carry out the various improvements will appear in detail from the following specification and by reference to the accompanying drawings in which—

30 Figure 1 is a side view of a cloth cutting machine embodying my invention, with the upper part of the machine broken away and with parts in section. Fig. 2 is a plan view of the handle and adjacent parts. Fig. 3 is 35 a sectional detail view of the guard taken on line 3—3 of Fig. 1. Fig. 4 is a plan detail view partly in section of the sharpening means and adjacent parts immediately beneath the motor. Fig. 5 is a sectional view 40 taken on line 5—5 of Fig. 4, and Fig. 6 is a view of a brake mechanism. Fig. 7 is a somewhat diagrammatic view showing a part of my invention applied to a cutter having a reciprocating knife.

45 As illustrated in the drawings the machine comprises the following main elements, a motor 10, a knife 11 driven by the motor, a standard 12 for the support of the various parts, a base 13, a switch mechanism 50 14, a handle 15, the sharpening means 16 and the knife guard 17. The base 13 is of usual construction for this type of machine. Suitably secured to it is the standard 12 which generally is in the form of a one-piece casting 55 provided with a stud 18 on which the knife rotates. The standard in its form and

construction embodies some of the features of my invention. It is bored out and shaped to form a socket 19 which is split as at 20, Fig. 4, and it is also provided with a curved 60 groove 21 for the reception of the knife guard 11.

The motor 10 comprises the usual commutator and brushes, not shown as their construction is not novel as far as this disclosure is 65 concerned, the armature 23, the field coil 24 and the pole pieces 25. The core 26 of the field coil is apertured at 27, and through the aperture 27 passes a sleeve 28 having an enlargement 29 which fits within the aforesaid 70 socket 19 in the standard. The sleeve 28 serves as a bushing for the armature shaft 30, which is provided with a shoulder 31 bearing against washers 32 which rest on the bushing 28. The bushing or sleeve 28 is 75 clamped firmly in the socket 19 by screws 33 as shown, and the core 26 of the field coil is pinned to the sleeve 28 by a pin 22. Thus the sleeve 28 is the sole connecting member 80 between the standard and the motor and is 85 the sole direct supporting means for the latter. 34 is a pinion suitably secured to the armature shaft and which drives the gear 35 secured to the knife. By means of this construction the motor may be entirely assembled as a unit, the sleeve 28 inserted and clamped to the core 26, the pinion 34 secured to the shaft, and thereafter the parts are 90 mounted by dropping the sleeve into the socket 19 and clamping it.

One object of the invention is to construct the machine in such a manner that the power is cut off automatically when the machine is not in use. To this end the following means are provided: The handle 15 is in this instance divided into a fixed portion 37 and a movable portion 38. 39 is a bracket secured to the machine for the support of the fixed handle portion 37 and to which the movable handle portion 38 is pivoted by a pin 40. 41 is a spring which normally keeps the handle portion in upward or "off" position, in which case the lever 42 of the switch 14 is automatically pushed upward or into "off" position by the yielding link 43 connecting 100 said lever to the handle portion 38. It follows that when the operator of the machine puts his hand on the handle and closes the same, the power is automatically turned on 105 and vice versa.

Another object of the invention is to provide means for automatically moving the

guard down in front of the knife when the power is off and the machine not in use. The guard is in the form of a curved plate 17 having an enveloping portion 45 which 5 envelopes or overlaps the knife 11 as best seen in Fig. 3. A curved rack 46 is secured to the guard at 47 and slides into the aforesaid groove 21 in the standard when the guard is up. The rack 46 meshes with a 10 gear 48 secured to the shaft 49, Fig. 5, which is journaled in lugs 50, 50 of the standard or frame 12. 51 is a gear secured to the shaft 49 by a screw 52. 53 is a gear which is formed with a collar 54 and which is loose 15 on the shaft 49, but clutched into or in driving engagement with the gear 51 by means of the said screw 52, the head of which projects into a recess 55 in the gear and collar 53-54. 56 is a spring which keeps the gear 20 53 in driving engagement with the gear 51. 57 is a rack which engages the gear 53 to rotate the latter. The said rack is slotted and in the slot 58 moves a pin 60 fast in the end of the arm 61 which latter is secured 25 to the movable handle portion 38 on the pin 40, Fig. 2. 62 is an adjustable stop on the rack 57. It is in the form of a housing which slides on said rack and which is provided with teeth 63 which engage the teeth 30 of the rack, by reason of the expansion of the spring 64 within the stop 62. The latter is moved on the rack 57 by depressing the housing 62 to free the teeth 63 from the rack after which the stop may be adjusted on the rack. The operation of these 35 parts is as follows: When the handle is closed by the operator the arm 61 is swung upwardly on the pivot 40 and the pin 60 in said arm strikes the stop 62 on the rack 40 57 moving the latter forwardly or to the right in Fig. 1. This causes a clockwise rotation of the gear 53 which through the screw 52 rotates the shaft 49 and gear 48. The rotation of the latter causes the rack 46 45 and with it the guard 17 to be moved upward to expose the cutting portion of the knife. In other words the operation of the handle automatically moves the guard as described through the instrumentalities 50 described immediately above. This construction presents several advantages. When the machine is not in use, the knife is at all times guarded to prevent accident. Again, when the operator commences to cut, he does 55 not have to use his hands to remove the guard from the knife.

In order to sharpen the knife, the guard 60 must be moved upward as explained and the sharpening wheels brought into contact with the knife while the latter is being rotated. These operations are accomplished by the following means: The sharpening wheels 16 are mounted as usual in front of the knife in a bracket 65 which is pivoted on the aforesaid shaft 49. A spring 66—Fig. 4—

normally keeps the wheels 16 away from the knife in the position shown in Fig. 1. 67 is a rack adapted to engage the aforesaid gear 51 fast to the shaft 49. The rack is operated by an arm 68 fast on a shaft 69 to which shaft a thumb piece 70 is secured. The rack 67 is provided with a blank portion, without teeth, indicated at 71 and whereby the gear 51 may be rotated without being operated upon by said rack 67, as explained above. The rack 67 is further provided with a cam 72—Fig. 4—which, when the rack is operated, strikes the collar 54 and unclutches the latter and the gear 53 permitting rotation of the shaft 49 while the gear 53 remains idle. 73 is a pin in the shaft 49 and adapted to strike the bracket 65 at 74 to force the sharpening wheels downward—Fig. 4.

The operation is as follows: When it is desired to sharpen the knife, the operator first closes the handle and the guard is automatically moved upward to expose the cutting edge of the knife. During this operation the gear 51 is rotated but is not in engagement with the rack 67 because of the blank portion 71 of the latter. Next the operator depresses, with the right thumb, the finger piece 70 thereby lifting the arm 68 and moving the rack 67 forward, which first strikes the collar 54 by means of the rack-cam 72 to unclutch the gear 53 from the shaft 49 to prevent rotation of said gear while it is in engagement with its rack 57. The forward movement of the rack 67 thereafter causes rotation of the gear 51 and shaft 49, and the pin 73 is rotated and strikes the bracket 65 and moves the sharpening wheels into contact with the knife. When the operator lets go of the finger piece 70, the spring 76 brings the arm 68 back to normal position carrying with it the rack 67, and the aforesaid spring 66 moves the wheels 16 upward. As soon as the rack 67 has been returned to its normal position, the spring 56 automatically forces the gear 53 into clutch with the gear 51 and shaft 49. When the operator lets go of the handle portion 38, the handle is opened by the spring 41 and the rack 57 returned to its normal position where it is stopped by a stop 80 striking the housing 81 which oscillates on the shaft 49 and keeps the racks in contact with the gears. The return movement of the rack 53 rotates the shaft 49 in an anti-clockwise direction and lowers the guard 17.

From the foregoing it will be seen that I have provided novel means for mounting and supporting the motor; that means are provided whereby the guard is automatically operated depending upon whether the machine is in use or not, or whether the knife is to be sharpened; further that operating means for the grinding wheels are 125 130

ranged for coöperation with the operating means for the guard in the proper sequence.

Fig. 6 illustrates a brake mechanism in which 90 is a brake shoe suitably pivoted to the machine at 91 and connected to the aforesaid arm 61 by a link 92. When the operator lets go of the handle portion 38 the arm 61 is moved down as explained and the brake shoe 90 is automatically moved down to 10 brake the armature 23 or some other movable part of the machine whereby the knife is stopped immediately after the current is cut off.

Fig. 7 shows some of the above features applied to a straight knife machine. In this figure the same reference numerals are used as for Fig. 1. In addition the knife is marked 111 and the guard 117 which carries the rack 146. The closing of the handle 20 operates the rack 57 and gear 53 to rotate the shaft 49 which carries the gear 48 which in turn meshes with the rack 146 to lift the guard 117. 100 represents a knob or handle for moving the shaft 49 sidewise, after 25 which the guard may be adjusted vertically by hand.

With reference to the operation of the guard it is to be noted that the guard is always guarding the operator's hand above the cloth to be cut and that the stop 62 is 30 adjusted to move the guard a predetermined distance.

While I have described the invention with reference to a specific disclosure it will be understood that I do not wish to be limited thereto but that the construction may be varied within the scope of the claims.

I claim:—

1. The combination of a standard, a knife 40 mounted thereon, a motor for driving said knife, a supporting member for said motor projecting through a portion of the same and means for clamping said supporting member to the said standard.

45 2. The combination of a standard, a knife, a motor for operating said knife, and comprising a field coil and core, supporting means for said motor, means for securing said field coil and core to the said supporting means and means for securing the latter to the said standard.

50 3. The combination of a standard, a knife, a motor for operating said knife and comprising a shaft, a field coil and core, a member disposed within the field coil and core and adapted to receive the said motor shaft to support the motor, means for securing said field coil and core to the said member and means for securing the latter to the said standard.

55 4. The combination of a standard, a knife, a motor for driving said knife and comprising an armature, a vertically disposed armature shaft and a horizontal field coil and core, a bushing extending through said field

coil and core and surrounding the said armature shaft, means for securing the field coil and core to the said bushing and means for securing the latter to the said standard.

5. The combination of a standard, a knife, 70 a motor comprising an armature, an armature shaft and a field coil and core, said armature shaft extending downwardly through said field coil and core, and a sleeve clamped to said standard and extending upwardly through said field coil and core, and adapted to receive said armature shaft and to support said motor.

6. In a cloth cutting machine the combination of a knife, a motor for operating it, 80 a switch mechanism controlling the current to the motor, an operating handle, a movable portion on the same, means for automatically moving said movable handle portion into an off position when said machine 85 is not being operated and means for automatically operating said switch mechanism to cut off the current for the motor when said handle portion is moved into its off position.

7. In a cloth cutting machine the combination of a standard, a rotatable knife mounted thereon, a motor supported above said standard and knife for rotating the latter, a switch mechanism for controlling the 95 current to the motor, automatic means for operating said switch mechanism to cut off the current from said motor when the said machine is not being operated and operating connections between said automatic means 100 and the said handle.

8. In a cloth cutting machine the combination of a standard, a knife, a motor for operating the latter, a handle, a movable portion thereon, a switch mechanism controlling the current to said motor, automatic means for moving said movable handle portion into an off position when said machine is not being operated and automatic means for simultaneously therewith operating said switch mechanism to cut off the current to the said motor.

9. In a cloth cutting machine the combination of a knife, a motor for operating it, 115 a switch mechanism, an operating member in the latter, an operating handle, a movable portion thereon, means for automatically moving the latter into an off position when said machine is not being operated and means for automatically operating said member in the switch mechanism when the said movable handle portion is moved into its off position.

10. In a cloth cutting machine the combination of a knife, a motor for operating it, 120 a switch mechanism controlling the current to said motor, an operating handle, a movable portion thereon adapted to be moved manually in one direction to operate the machine, means for automatically moving 125

- the movable handle portion into an off position when said machine is not being worked and connections between said movable handle portion and said switch mechanism for operating the latter to automatically cut off the current from said motor when said movable handle portion is moved into its off position and to turn the current on when said handle portion is manually operated.
- 10 11. In a cloth cutting machine the combination of a knife, a motor for driving it, a switch mechanism for the motor, an operating handle, a movable portion thereon, connections between the latter and the said switch mechanism and automatically operated means for maintaining said movable handle portion in an off position to operate the said switch mechanism to cut off the current from the machine when the latter is not being operated.
- 15 12. In a cloth cutting machine the combination of a knife, a guard for it, an operating handle, a movable portion thereon adapted to be moved into an operating position to operate the machine and into an off position when the machine is not being operated and means for automatically moving said guard into guarding position when said movable handle portion is moved into off position.
- 20 13. In a cloth cutting machine the combination of a knife, a guard normally guarding the same, an operating handle and means connected to the latter whereby said guard is automatically operated to expose said knife when the operator grasps the said handle to operate the machine.
- 25 14. In a cloth cutting machine the combination of a knife, a guard for the same, an operating handle, a movable portion thereon and means controlled by said movable handle portion for automatically operating said guard into a non-guarding position with relation to the said knife.
- 30 15. In a cloth cutting machine the combination of a knife, a guard for the same, means for operating said guard and devices for rendering said operating means inactive at predetermined moments during the operation of the machine.
- 35 16. In a cloth cutting machine the combination of a knife, a motor for operating said knife, a guard for the latter, an operating handle, a switch mechanism controlling the current to said motor and means for automatically cutting off the current from the motor and moving the said guard into guarding position when said handle is being manipulated by the operator.
- 40 17. In a cloth cutting machine the combination of a knife, a motor for operating said knife, a guard for the latter, a switch mechanism controlling the current to said motor, an operating handle and means connected to said handle for automatically cutting off the current from the motor and moving the said guard into guarding position when said handle is being manipulated by the operator.
- 45 18. In a cloth cutting machine the combination of a knife, a motor for operating said knife, a guard for the latter, a switch mechanism controlling the current to said motor, an operating handle, a movable portion thereon and means actuated by said movable handle portion for cutting off the current from the motor and moving said guard into guarding position.
- 50 19. In a cloth cutting machine the combination of a knife, a motor for operating the same, a guard for said knife, a switch mechanism controlling the current to said motor, an operating handle, a movable portion thereon and automatic means for maintaining said movable handle portion in an off position, the said guard in its guarding position and for operating said switch mechanism to cut off the current from the said motor while the said machine is not being operated.
- 55 20. In a cloth cutting machine the combination of a standard, a knife mounted thereon, a guard and sharpening means located in front of said knife, a handle located in the rear of said knife, a movable portion on said handle and connections between said movable handle portion and the said guard and sharpening means for operating the same located to the one side of the said standard.
- 60 21. In a cloth cutting machine the combination of a knife, a guard and sharpening means for said knife, a shaft operatively connected to said guard and sharpening means, a gear on said shaft for operating said guard, a second gear on said shaft for operating the said sharpening means and mechanism for rendering said first gear inactive when the said second gear is operated.
- 65 22. In a cloth cutting machine the combination of a knife, a guard and sharpening means for said knife, a shaft operatively connected to said guard and sharpening means, gears on said shaft in driving connection therewith for operating said guard and sharpening means and means for unclutching the guard operating gear from the said shaft when the sharpening means operating gear is being operated to actuate the sharpening means.
- 70 23. In a cloth cutting machine the combination of a knife, a guard and sharpening means for said knife, an operating handle, a movable portion thereon, means for operating said guard from the said movable handle portion and means adjacent to said handle for operating the said sharpening means.
- 75 24. In a cloth cutting machine the com- 130

5 bination of a knife, a guard and sharpening means for the same, a shaft, means for rotating said shaft a distance in one direction to operate the said guard, other means for rotating said shaft a further distance in the same direction to operate the said sharpening means and a mechanism for actuating the said rotating means.

10 25. In a cloth cutting machine the combination of a knife, a guard and sharpening means for the same, a shaft, a first gear fast on said shaft for operating said sharpening means, a second gear loose on said shaft for operating said guard, a clutch mechanism for normally clutching said second gear to the said first gear, mechanism for rotating the first gear and means for automatically unclutching said second gear when the said first gear is operated.

15 20 26. In a cloth cutting machine the combination of a knife, a guard and sharpening means for the same, a shaft, a first gear fast on said shaft for operating said sharpening means, a second gear loose on said shaft for 25 operating said guard, a clutch mechanism for normally clutching said second gear to the said first gear, mechanism for rotating the first gear and means operated by said mechanism for automatically unclutching 30 said second gear when the said first gear is operated.

20 27. In a cloth cutting machine the combination of a knife, a guard for said knife, a gear for operating said guard, a shaft to 35 which said gear is secured, a second gear loosely mounted on said shaft, clutching means for operatively connecting said second gear and shaft, a rack for operating said gear, means for operating said rack and 40 means for adjusting the movement of the latter.

28. In a cloth cutting machine the combination of a knife, sharpening means for

the said knife, a shaft, a gear for operating said sharpening means, secured to said 45 shaft, a rack for operating the latter and means for actuating said rack.

29. In a cloth cutting machine, the combination of a knife, a guard for said knife, an operating handle, a movable handle portion thereon having an operable and an off-position and connections controlled by said movable handle portion for automatically moving said guard into non-guarding position when said movable handle portion is 50 moved into its operable position and for automatically moving said guard into 55 guarding position when said handle portion is moved into its off position.

30. In a cloth cutting machine, the combination of a knife, a guard for said knife, an operating handle, a movable handle portion thereon having an operable and an off-position and connections controlled by said movable handle portion for automatically 60 moving said guard into non-guarding position when said movable handle portion is moved into its operable position and for automatically moving said guard into 65 guarding position when said handle portion is moved into its off position, and means for automatically moving said handle portion 70 into its off position.

31. The combination of a knife, a movable guard for the same, a brake for said knife, 75 a movable handle and connections between the latter and the said knife guard and brake for automatically moving said guard into guarding position when the said brake is being applied.

80 Signed at New York, N. Y., this 16th day of July 1914.

EDWARD M. WARING.
